CLAIM

The ornamental design for a set of double-sided twist hoop earrings with faceted stones in a channel, as shown and described.

DESCRIPTION

FIG. 1 is a front perspective view of a first embodiment of a set of double-sided twist hoop earrings with faceted stones in a channel according to the new design;

FIG. 2 is a top plan view thereof;

FIG. 3 is a bottom plan view thereof;

FIG. 4 is a view of outer sides thereof;

FIG. 5 is a view of inner sides thereof;

FIG. 6 is a front view thereof;

FIG. 7 is a rear view thereof;

FIG. 8 is a front perspective view of a second embodiment of a set of double-sided twist hoop earrings with faceted stones in a channel according to the new design;

FIG. 9 is a top plan view thereof;

FIG. 10 is a bottom plan view thereof;

FIG. 11 is a view of the outer sides thereof;

FIG. 12 is a view of the inner sides thereof;

FIG. 13 is a front view thereof; and,

FIG. 14 is a rear view thereof.
